TANK SUPPORT

Donald B. Tolley, Macomb, Ill., assignor to Globe American Corporation, Kokomo, Ind., a corporation

Application October 5, 1939, Serial No. 297,968

1 Claim. (Cl. 220—18)

This invention relates to a tank support, particularly a simple and efficient means of supporting liquid containing tanks to a wall in elevated position.

The feature of the invention resides primarily in the provision of a narrow supporting bracket secured to a wall and extending therefrom only sufficiently to support the adjacent edge of the tank when mounted thereon, said bracket being provided with convenient means for interlocking the tank therewith. Associated with said bracket, there is provided a tie block spaced upwardly therefrom and secured to the wall, to which the upper adjacent wall of the tank may be permanently or removably tied to prevent its tipping off of the bracket support.

The full nature of the invention will be understood from the accompanying drawing and the following description and claim:

Fig. 1 is a central vertical section through the supported tank, bracket and tie block with the tank in supported position. Fig. 2 is a plan view of the lower bracket support with the tank removed, but its position indicated in dotted lines. Fig. 3 is a section taken on the line 3—3 of Fig. 1.

In the drawing there is illustrated a wall 10 upon which a cylindrical drum tank 11 is to be supported. The tank is provided with the usual annular flange 12 extending downwardly in continuation of its wall below the bottom 13. For supporting the tank there is secured to the wall 10 a bracket support in the form of a block 14 by means of screws 15, or any suitable means. The block is provided with an upper flat surface which is coextensive with an arcuate portion of the flange 12 on the tank, in which there is provided a corresponding arcuate groove 16 to form an interlocking shoulder with the flange 12. Thus, an arcuate portion of the flange 12 is adapted to seat within the groove 16 so as to interlock with the shoulder formed thereby, whereas the upper surface of the block may or may not be in supporting relation with the bottom 13 of the tank. The arcuate portion of the flange 12, which is seated in the groove, preferably extends about 60 degrees of the periphery thereof.

The tank is retained in its interlocked supporting relation with the bracket 14 by the tie block

17 secured to the wall 10 by screws 18 or similar suitable means. The tie block 17 is positioned to be engaged by the peripheral wall of the tank immediately below the top thereof and it is provided with an exposed forward surface or edge conforming with the shape or contour of the tank wall so that the tank lies snugly thereagainst. While the screws, or the like, 18 secure the tie block to the wall, they may likewise extend through the wall of the tank so that their heads 19 will primarily lock the tank to the tie block. The tank may be perforated to receive the screws 18, or the usual keyhole apertures may be provided in the upper wall of the tank to permit removable interlocking with the heads of the screws or the like.

The weight of the tank will be received and supported by the bracket 14 with which it is interlocked through the shoulder groove and flange, while the tank is tied to the wall against tipping off of the supporting bracket and steadied in its proper position with respect thereto, by the tie block 17 and its associated securing means here shown in the form of screws 18.

The invention claimed is:

A structure for supporting a tank or the like on a wall in elevated relation, said tank having an annular flange extending downwardly from the bottom thereof, said structure comprising a pair of separate wooden blocks adapted to be supported upon said wall in vertical spaced relation, the lowermost of said blocks extending from the wall to partially underlie the bottom of the tank and provided with an arcuate groove formed therein conforming to the curvature of the bottom flange of said tank within which said flange is adapted to seat, the uppermost block having a forward arcuate surface conforming in contour to the wall of said tank and extending in vertical alignment with the groove formed in the lowermost block, means for securing the lowermost block to said wall in tank supporting position and a plurality of radially spaced screws extending through the wall of said tank and upper block adapted to secure said tank to said upper block and said upper block to its supporting wall.

DONALD B. TOLLEY.
